UNITED STATES PATENT OFFICE.

ABBOT AUGUSTUS LOW, OF NEW YORK, N. Y.

SAP-PAIL.

SPECIFICATION forming part of Letters Patent No. 659,373, dated October 9, 1900.

Application filed January 13, 1900. Serial No. 1,265. (No model.)

To all whom it may concern:

Be it known that I, ABBOT AUGUSTUS LOW, a citizen of the United States, residing in the city of New York, borough of Brooklyn, in 5 the county of Kings and State of New York, have invented certain new and useful Improvements in Sap-Pails, of which the following is a specification sufficient to enable others skilled in the art to which the invention appertains to make and use the same.

My invention relates to receptacles used for the collection of sap from trees, as the sap of the maple-tree. Such receptacles are exposed to varying conditions of wind and 15 weather and as ordinarily made admit more or less extraneous matter to the interior—as rain, dust, &c.—thereby contaminating the sap and causing trouble and expense in purifying the sap and cleaning the pail.

20 My present invention is designed to effectually exclude all foreign matter from the sap-pail, to insure the shedding of the rain from the cover thereof without internal leakage, and to simplify the means of attachment 25 between the cover and pail.

The invention consists in combining with a pail the top of which is formed upon an inclined plane with relation to the body thereof of a dish-shaped cover having a spout at the 30 lower portion which fits under the adjoining portion of the rim of the pail, and thereby locks the parts against accidental displacement, the dishing shape of the cover and its spout being designed to collect and insure the discharge of the rain, snow, &c., without danger 35 of communication with the interior. The invention also includes the employment of means in the construction of the can-body for ventilating the space above the sap contained in the receptacle, said means of ventilation also affording means for discharging, straining, or filtering the sap without the removal of the cover.

In the accompanying drawings, Figure 1 is 45 a central vertical section of my improved sap-pail and cover. Fig. 2 is a plan of the cover. Fig. 3 is an elevation of the pail and cover; Fig. 4, a vertical section taken at right angles to Fig. 1.

50 A represents a sap-pail having its rim a

upon a plane inclined with relation to the central axis of the pail, substantially as set forth in my concurrent application, Serial No. 1,264, filed January 13, 1900. *h* is the perforation by which the receptacle is suspended upon the tree in the ordinary manner. The cover *C* is preferably formed in one piece from sheet metal with the depressed center or dish *c* and the upright internal flange *c'* and downwardly-projecting external 60 flange *c''*, the curve *c''*, between the two recurved flanges *c'* *c''*, being conformable to the rim of the pail, so as to fit thereover snugly, and thus seal the receptacle against the admission of extraneous matter of any kind. 65 The lower portion of the cover is formed with a spout *s*, which fits into and projects through a slot *a'*, formed in the body of the pail below the rim *a*. Thus the spout *s* performs a double function in that it insures the discharge of snow or rain, &c., collected in the dish *c* and at the same time by its engagement with the rim *a'* locks the cover in place. By this means I obviate the use of all spring-bolts or other special appliances for attaching 70 the cover to the pail and greatly simplify and cheapen the construction of the device. Near the upper end of the pail and just below the position of the cover I form a series of perforations *p*, which allow a certain 75 amount of circulation of air to and from the interior of the receptacle. These perforations also afford a means of discharging the contents of the pail without removing the cover, the sap being strained and filtered as 80 discharged. It is obvious that wire-gauze or any other mechanical expedient may be substituted for the perforations *p* (shown in the drawings) with like result. This construction of my improved sap-pail affords adequate 85 protection to the sap collected therein, while the cover can be quickly and conveniently applied or removed.

What I claim as my invention, and desire to secure by Letters Patent, is—

1. The combination of a sap-pail having an inclined rim with a dish-shaped cover fitting thereon, formed at its lower extremity with a spout for the purpose set forth.

2. The combination of a sap-pail having an

- inclined rim and formed with a slot under said rim with a dish-shaped cover formed with a spout adapted to project through said slot for the purpose set forth.
- 5 3. The combination of a sap-pail A, formed with the inclined rim a , and with the slot a' , with the dish-shaped cover C, formed with the open spout s , for draining the top of the cover, and for engagement with the rim a , substantially as set forth.
- 10 4. The combination of a sap-pail A, formed with the inclined rim a , and with the slot a' ,

with the dish-shaped cover C, formed with the recurved flanges c' , c^2 , for the purpose described.

15 5. The combination of the sap-pail A, having the inclined rim a , and formed with the perforations p , with the cover C, interlocking with said rim of the pail for the purpose set forth.

ABBOT AUGUSTUS LOW.
